Application June 9, 1933, Serial No. 675,125

2 Claims. (Cl. 20—2)

The present invention relates to new and useful improvements in cabins for use particularly by automobile tourists and has for its primary object to provide, in a manner as hereinafter set forth, a cabin of this character embodying a novel construction, combination and arrangement of parts through the medium of which said cabin may be expeditiously folded when not in use in a manner to occupy a minimum of space to facilitate moving the same from place to place.

Other objects of the invention are to provide a folding cabin of the aforementioned character which will be simple in construction, strong, durable, weatherproof, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation, showing the cabin in folded position.

Figure 2 is a side elevational view, showing the cabin in unfolded position.

Figure 3 is a view in end elevation, showing the cabin in folded position.

Figure 4 is a view in end elevation, showing the cabin in unfolded position.

Figure 5 is a view in vertical longitudinal section through the cabin, taken substantially on the line 5—5 of Figure 4.

Figure 6 is a view in vertical longitudinal section through the cabin when in folded position.

Figure 7 is a horizontal sectional view, taken substantially on the line 7—7 of Figure 4.

Figure 8 is a detail view in elevation, showing one of the swinging supporting legs in inoperative position.

Figure 9 is a detail view in perspective, showing the locking means on the foldable side walls for engagement with one of the end walls.

Figure 10 is a detail view in elevation, showing the locking means on the shiftable end wall which is engageable with the member shown in Figure 9.

Figure 11 is a detail view showing the locking means on the shiftable end wall, taken at right angles to Figure 10.

Referring now to the drawings in detail, it will be seen that the embodiment of the invention which has been illustrated comprises a rigid or fixed section which is designated generally by the reference numeral 1 upon which is mounted a

foldable section or extension which is designated generally by the reference numeral 2. The fixed section 1 includes an end wall 3, side walls 4 having windows 5 therein, and a transversely arched roof 6. A platform 7 constitutes the bottom of the fixed section 1 of the cabin.

The foldable extension 2 comprises side walls 8 which are hingedly connected, as at 9, to the side walls 4 of the fixed section 1. The reference numeral 10 designates a pair of hingedly connected floor sections for the foldable extension 2, one of which is hingedly connected, as at 11, to the riser 12 of the platform 7. The other floor section 10 is hingedly connected to an end wall 13, as at 14. It may be well to here invite attention to the fact that the side walls 4 of the fixed section 1 of the cabin project beyond the riser 12 of the platform 7. This is illustrated to advantage in Figure 5 of the drawings. A cleat 15 projects from the lower portion of the end wall 13 beneath the hinge connection 14 to assist in supporting the floor sections 10 when in extended or operative position. A pair of pivotally connected links 16 extends between each of the side walls 4 of the fixed section 1 and the end wall 13 of the extension 2 for limiting the movement of the said end wall 13 away from said fixed section 1. The pairs of links 16 are, of course, pivotally connected to the side walls 4 and to the end wall 13. A brace 17 extends from the pivotally connected ends of the pairs of links 16 to the hinge joint 18 of the floor sections 10.

The reference numeral 19 designates a collapsible, flexible roof of suitable material which extends between the hinged side walls 8 of the extension 2 when said extension is in operative position, said roof 19 being connected, at one end, to the end wall 13 and having its other end portion extending beneath the roof 6 and anchored to the fixed section 1 of the cabin. Hingedly mounted in the end wall 13 of the extension 2 is a door 20, a suitable button 21 being provided for securing said door in closed position.

When in unfolded position, the extension 2 is supported on retractable legs 22 which are mounted on brackets 23 which project from the free end portions of the side walls 8 through the medium of pin and slot connections 24. This is illustrated to advantage in Figure 8 of the drawings. When it is desired to swing the legs 22 to operative position, as suggested in broken lines in Figure 8, said legs are first moved vertically and then swung outwardly and downwardly until arrested by engagement with the free ends of 110

the side walls 8. Then, the weight of the extension 2 causes the pins of said legs to move upwardly in the slots of the brackets 23 until arrested by engagement with the upper end walls 5 of said slots in which position swinging movement of said legs is prevented.

Socket members 25 are mounted on the inner sides of the free end portions of the walls 8 for engagement in recesses 26 in the end wall 13 10 in a manner to receive lugs 27 on the vertical edges of said end wall for releasably locking the end wall in extended position and for securing the side walls thereto.

The reference numeral 28 designates a bed 15 which is pivotally mounted, as at 29, between the side walls 4 of the fixed section 1. When the cabin is in unfolded position for use, the bed 28 is adapted to rest on the platform 7 and project into the extension 2, as seen in Figure 5 20 of the drawings. When not in use, the bed 28 is swung upwardly to the position shown in Figure 6 of the drawings to permit folding of the extension 2.

When the extension 2 of the cabin is to be 25 folded, the links 16 are broken upwardly as are also the hingedly connected floor sections 10, this movement of the links and floor sections being caused to take place simultaneously by reason of the connecting braces 17. The end wall 30 13 may then be moved toward the fixed section 1 of the cabin until said end wall, the floor sections 10, the links 16, the braces 17 and the collapsible flexible roof 19 are positioned between the projecting end portions of the side walls 4. 35 Of course, the bed 28 has previously been swung upwardly to the position shown in Figure 6 of the drawings. Then, the side walls 8 are swung inwardly across the end wall 13, said side walls overlapping each other when in closed or folded 40 position, suitable buttons 30 being provided for securing the side walls in folded position. Of course, when the extension 2 is folded, the legs 22 are swung upwardly to retracted or inoperative position, as suggested in Figure 3 of the drawings. It will thus be seen that the cabin, when 45 folded, is very compact and requires comparatively little space. The reference numeral 31 designates supporting legs which may be provided for the fixed section 1 of the cabin.

To unfold the extension 2, the side walls 8 are 50 swung outwardly to open position on their hinges 9 and the legs 22 are swung downwardly to operative position. Then, the end wall 13 is moved horizontally away from the fixed section 1 of the cabin, thus permitting the links 16 and the 55 floor sections 10 to unfold to operative position, and the lugs 27 are engaged in the socket members 25. The bed 28 is then swung downwardly until it rests in a horizontal position on the platform 7 and the cabin is then ready for use. It will thus be seen that a portable cabin has 60 been provided which may be conveniently transported from place to place and set up for use.

It is believed that the many advantages of a 65 folding, portable cabin constructed in accordance with the present invention will be readily understood and although the preferred embodiment of the invention is as illustrated and described, it is to be understood that changes in the 70 details of construction and in the combination and arrangement of parts may be resorted to which

will fall within the scope of the invention as claimed.

What is claimed is:

1. A cabin comprising a rigid section including side walls, a roof and a floor portion, said side walls projecting beyond the floor portion at one end of said section and the roof projecting beyond said side walls of said one end, a pair of side members hingedly connected to the side walls at said end of the rigid section and adapted to be folded inwardly under the projecting portion of the roof, a rear wall member, a flexible roof portion connected to the upper edges of said rear wall member and the side members and to a portion of the upper portion of the rigid section, a pair of floor sections hingedly connected together, means for hinging one section to the lower end of the rear wall member on the inner face of said member, means for hinging the other section to the floor portion of the rigid section of the cabin, said floor sections being adapted to be swung upwardly into the lower portion of the space formed by the extended ends of the side walls of the rigid section and the rear wall member being adapted to be moved into the space formed by the projecting portions of the side walls and the roof of the rigid section and the side wall members being adapted to be folded over said end wall member when the same has been moved into said space, means for holding the side wall members together in folded position, and releasable means for holding the rear wall member and the floor section in extended position. 90

2. A cabin comprising a rigid section including side walls, a roof and a floor portion, said side walls projecting beyond the floor portion at one end of said section and the roof projecting beyond said side walls of said one end, a pair of side members hingedly connected to the side walls at said end of the rigid section and adapted to be folded inwardly under the projecting portion of the roof, a rear wall member, a flexible roof portion connected to the upper edges of said rear wall member and the side members and to a portion of the upper portion of the rigid section, a pair of floor sections hingedly connected together, means for hinging one section to the lower end of the rear wall member on the inner face of said member, means for hinging the other section to the floor portion of the rigid section of the cabin, said floor sections being adapted to be swung upwardly into the lower portion of the space formed by the extended ends of the side walls of the rigid section and the rear wall member being adapted to be moved into the space formed by the projecting portions of the side walls and the roof of the rigid section and the side wall members being adapted to be folded over said end wall member when the same has been moved into said space, means for holding the side wall members together in folded position, and releasable means for holding the rear wall member and the floor section in extended position, such means including a pair of links pivotally connected together and one link being pivoted to a part of the rigid section and the other pivoted to the rear wall member, and a third link pivoted to the junction of the pair of links and to the hinged connection between the pair of floor sections. 110
